UNITED STATES PATENT OFFICE.

MICHAEL F. SULLIVAN, OF SAN FRANCISCO, CALIFORNIA, ASSIGNOR, BY DIRECT AND MESNE ASSIGNMENTS, TO AUTOMATIC RAILWAY STREET AND STATION INDICATOR AND ADVERTISING CO., OF SAN FRANCISCO, CALIFORNIA, A CORPORATION OF CALIFORNIA.

INDICATOR.

1,128,196.

Specification of Letters Patent.

Patented Feb. 9, 1915.

Application filed May 29, 1913. Serial No. 770,687.

To all whom it may concern:

Be it known that I, MICHAEL F. SULLIVAN, a citizen of the United States of America, residing at San Francisco, in the 5 county of San Francisco and State of California, have invented certain new and useful Improvements in Indicators, of which the following is a specification.

This invention relates to indicators and, 10 more especially, to that class of indicators adapted for use on railway coaches and the like to announce automatically the next stopping place of the train.

The objects of this invention are; to provide an indicator which is simple and cheap 15 of construction and accurate in operation; to provide an indicator with automatic means for changing the display on the indicator face at any predetermined points 20 along the route of travel; to provide simple and efficient means for resetting said indicator.

With these and such other objects in view as may hereinafter more fully appear, my 25 device consists in the novel arrangement and construction of parts hereinafter more fully described and claimed, and which are shown in the accompanying drawings, wherein—

30 Figure 1 is a perspective view of a car truck with the motor-wheel for the indicator attached thereto. Fig. 2 is a perspective view of the indicator, the casing being removed.

35 Referring to said drawings by numerals, a car truck 1 has fastened thereto in any suitable and convenient manner a bracket 2, the arm of said bracket being hinged at 3 and carrying, at its outer extremity, the enlarged cylindrical portion 4 bored throughout 40 its length to form a journal for the shaft 5 of the motor or drive-wheel 6. The purpose of the hinge 3 in the arm of bracket 2 is to allow for inequalities due to 45 the rise and fall of the truck 1 caused by the roughness of the road bed.

Fastened to shaft 5, and constrained to turn therewith, is a flexible shaft 7 having its other end made fast to a shaft 8 journaled in brackets 9 which are fastened to the side wall of the casing or cover. Shaft 8 carries a worm 10 adapted to engage the teeth of worm-wheel 11. The shaft 12 of

worm-wheel 11 is journaled in suitable journal boxes formed in the side walls of the 55 casing and carries a helix 13 wound thereon and constrained to revolve therewith.

Helix 13 is provided, upon its periphery, with suitably spaced, radially extending teeth or projections 14, for a purpose herein- 60 after fully set forth.

A grooved wheel or trolley 15 rests upon the periphery of the helix 13, said wheel being revolvably and slidably mounted on a pin or shaft 16 carried by the bifurcated end 17 65 of arm 18 of a bell-crank lever fulcrumed at 19 to a bracket or support 20 carried by the casing. The other arm 21 of said bell-crank lever terminates in a clutch throwing member 22 which engages, by sliding 70 contact, one member or plate 23 of a clutch. Said bell-crank lever is held in normal position by any suitable means but preferably by a resilient member or spring 24 one end of which is made fast, through an eye there- 75 in, to ear 25 carried by arm 18; the other end of said spring being fastened to the eye of screw 26 which passes through a suitable recess formed in a bracket 27 carried by the casing, said screw permitting of adjustment 80 of the tension of said spring by the thumb nut 28 which engages said screw.

As will be readily seen, when motion is imparted to the helix 13 through the worm and worm-wheel, the trolley 15 will ride on 85 the periphery thereof, sliding along pin 16 as it travels. When said trolley comes in contact with one of the teeth 14, it will be lifted, thereby operating the bell-crank lever and throwing plate 23 of the clutch, 90 for a purpose which will hereafter appear.

Shaft 8 carries a clutch member, or plate, 29 which is retained upon said shaft by the collar 30 against which said plate is held by the resilient member or spring 31. While 95 the clutch member 29 is free to slide upon shaft 8, it is constrained to revolve therewith by the key 32.

Clutch member 23 is slidably mounted upon one end of a shaft 33 with which it is 100 constrained to revolve by the key 34. Said shaft 33 is journaled in a bracket or support 35 carried by the casing, and carries on its other end a bevel-wheel 36 adapted to engage bevel-wheel 37 carried by a shaft 105 38. Shaft 38 is further provided, at or

near its extremities, with bevel-wheels 39 and 40 adapted to engage the bevel ends of rollers 41 and 42 respectively. Said rollers 41 and 42 are carried on shafts having their ends journaled in suitable journal boxes formed in the casing.

Rollers 41 and 42 are provided around the surfaces thereof with suitably spaced, radial projections or spurs 43 and 44 adapted 10 to engage spaced recesses 45 formed near the edges of a band or belt 46 which passes over said rollers 41 and 42 and is wound upon drums 47 and 48 mounted upon shafts 49 and 50, respectively, the ends of said 15 shafts being journaled in suitable bearings carried by the casing.

Carried by shafts 49 and 50 and adjoining the drums 47 and 48 are the oppositely disposed cones 51 and 52 connected by a 20 flexible, resilient member of any suitable form and material, but preferably composed of a cable 53 having interposed therein the coiled spring 54. As will be readily understood, said cable acts as a driving means between the drums, the resilient member 54 tending to preserve the proper tension at all 25 times and the oppositely disposed cones, upon which said cable winds, acting to compensate for the change in diameter of the drums due to the unwinding of the belt 30 from one and its winding upon the other.

Belt 46, in passing over rollers 41 and 42, is guided before the indicator face 55 formed in the casing and, as said belt carries upon its surface the street or station 35 names desired, the same are successively shown, as will be described.

A crank 56 is provided at one end of shaft 38 for the purpose of manually adjusting the 40 position of belt 46 should the same become desirable.

A push button 57, adapted to extend through the casing, is carried on one end of the rod 58 the other end of which is pivotally connected to one arm 59 of a bell-crank lever fulcrumed at 60 to a suitable support 61 carried by the casing. The other arm 62 of said bell-crank lever terminates in a clutch engaging member 63 which is in 45 sliding engagement with clutch member 29. The purpose of said push button 57 and its connection through the bell-crank lever with clutch member 29 is, to release the clutch by pressure upon said button in case it is desired 50 to change the position of belt 46 at a time when the clutch members are normally in engagement.

For the purpose of calling attention to the indicator at the time of change in the 55 belt setting, an extension or rod 64 provided at its outer extremity with a knob or clapper 65 is carried by arm 21 of the bell-crank lever, and a bell 66 fastened to a suitable support carried by the casing is so placed as 60 to be struck by said clapper upon the move-

ment of said bell-crank lever due to the trolley 15 riding upon one of the teeth 14 of the helix 13.

The operation of the device is as follows:—The drive-wheel 6, being in contact with the rail, is revolved when the car is in motion, imparting revolution through its axle 5 and flexible shaft 7 to shaft 8 and worm 10. Worm 10, through engagement with worm-wheel 11, imparts motion to helix 13. When helix 13 has revolved through a sufficient arc to bring trolley 15 in contact with a tooth 14, the trolley is lifted, thereby lifting the end of arm 18 and causing a throw of end 22 of arm 21; 15 this causes clutch member 23 to be thrown into engagement with clutch member 29, which is revolving with shaft 8. Revolution is then imparted to shaft 33 and from thence, through the bevel gears, to shaft 38. The 20 motion of shaft 38 is in turn imparted, through the bevel gears, to rollers 41 and 42, which causes movement of the belt 46, thereby changing the display at indicator face 55.

It will of course be understood that the 25 drive-wheel, worm and worm-wheel are proportioned and the positions of the teeth on the helix are regulated by the road on which the device is to be used and the distance between stations or stops thereon.

Having described my invention, what I claim as new and desire to secure by Letters Patent, is:—

1. In an indicator, a pair of alined shafts, a clutch member connected to each shaft, a bell crank lever having a vertical arm connected to the clutch member of one shaft and having a horizontal arm arranged in spaced overlying relation to the other shaft, and pivoted at the juncture of its said arms 100 means actuated by said other shaft and arranged in the space between the latter and said horizontal arm of the lever for periodically operating said lever to effect movement of the free end of the vertical arm toward said means whereby to cause coupling of the clutch members, spring means to tension the bell crank lever arranged between said means and the vertical arm of the bell-crank lever and secured to the horizontal 105 arm of the bell crank lever in depending relation thereto, and signal display means 110 operated by the first named shaft.

2. In an indicator, a pair of alined shafts, a clutch member connected to each shaft, 115 a pivoted bell crank lever having a vertical arm connected to the clutch member of one shaft and having a horizontal arm arranged in spaced overlying relation to the other shaft, means actuated by said other shaft and arranged in the space between the latter and said horizontal arm of the lever 120 for periodically operating said lever to effect movement of the free end of the vertical arm toward said means whereby to 125

cause coupling of the clutch members, means capable of manual operation having connection with the clutch of the second mentioned shaft for operating said clutch, 5 and signal means operated by the first named shaft.

3. In an indicator, a pair of alined shafts, a clutch member connected to each shaft, a pivoted bell crank lever having a vertical 10 arm connected to the clutch member of one shaft and having a horizontal arm arranged in spaced overlying relation to the other shaft, a helix having spaced projections arranged in the space between said other 15 shaft and the horizontal arm of the lever, means to rotate the helix from the second mentioned shaft, the free end of the hori-

zontal arm of the lever being forked, a shaft connected to said fork, a roller slideable on the shaft of said fork and being engaged with the helix and when engaging said helix projections being moved upwardly to thereby effect rocking movement of the free end of the vertical arm of the lever toward the helix to couple the clutch 20 members, means to rotate the helix from the second mentioned shaft, and signal display means operated by the first named shaft. 25

In testimony whereof I hereunto affix my signature in presence of two witnesses.

MICHAEL F. SULLIVAN.
